UNITED STATES PATENT OFFICE.

ROSA D. HATCH, OF MEMPHIS, TENNESSEE.

AMPLIFIER FOR TELEPHONES.

1,137,614.

Specification of Letters Patent. Patented Apr. 27, 1915.

Application filed December 7, 1914. Serial No. 875,978.

To all whom it may concern:

Be it known that I, ROSA D. HATCH, a citizen of the United States, residing at Memphis, in the county of Shelby and State of Tennessee, have invented certain new and useful Improvements in Amplifiers for Telephones; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in amplifiers or sound intensifying devices for attachment to receivers of telephones and consists essentially in the provision of a device of this nature attached to the receiver and in the provision of a lever-operated mechanism for raising the receiver-holding fork when it is desired to use the telephone.

My invention consists of various details of construction, combinations and arrangements of parts which will be hereinafter fully described, shown in the accompanying drawings and then specifically defined in the appended claims.

I illustrate my invention in the accompanying drawings, in which:

Figure 1 is a front elevation showing the application of the invention. Fig. 2 is a sectional view through the sound amplifier on line 2-2 of Fig. 1, and Fig. 3 is a detail view on line 3-3 of Fig. 1 showing the means for raising the receiver-holding member.

Reference now being had to the details of the drawings by letter, A designates a funnel-shaped horn having a contracted portion B to which a clamping member C is fastened and which in turn is pivotally mounted upon a pin D secured to the bar E.

F is a bolt which passes through one or another of the apertures H formed in said bar and a cylindrical or other-shaped washer, designated by letter I, is mounted upon the bolt F and J is adapted to engage the forks K of the usual receiver holder, and a thumb nut, designated by letter L, is mounted upon the threaded end of the bolt F and is adapted to clamp the forked arms of the receiver holder against said cylindrical washer and

the bar to hold the latter in an adjusted position. Said horn has a flaring end O with resilient fingers O' secured thereto and which are adapted to spring over the marginal edge of a receiver and has a central funnel-shaped extension M which extends to a position adjacent to the opening leading to the diaphragm of the receiver.

A lever, designated by letter Q, is provided with a forked end Q' adapted to engage the shank portion of the receiver holder and is pivotally mounted upon a pin R fixed to the bar S which in turn has a clamping member T secured thereto for engagement about the circumference of the telephone at any suitable location and which is held in position by means of a screw S' passing through registering apertures in the clamping member.

In operation, when the device is applied to a receiver in the manner shown and when it is desired to use the telephone, the operator by swinging the lever to an upright position will cause the receiver holder to be raised and the circuit opened for the use of the instrument, the vibrations coming from the receiver being intensified and the sound being sufficiently amplified so that the message may be heard at a distance without the necessity of holding the receiver to the ear. When it is desired to cut off the telephone, the operator by swinging the lever may allow the receiver holder to return by gravity to its normal position.

By the provision of the adjustable means, it will be noted that the amplifier may be held in various positions with relation to the telephone receiver holder, being clamped in position thereon and, if desired, the device may be easily and quickly detached from the receiver, as will be readily understood.

What I claim to be new is:-

1. A sound intensifier for telephones comprising a horn with a contracted portion and a flaring funnel-shaped part, a central conical, open-ended tubular extension within said flaring end with one end adapted to be positioned adjacent to the diaphragm of the receiver, a support for holding the horn upon a receiver holder, a clamping member, a pin pivotally connected thereto, an apertured bar secured to said pin, a bolt carried by the bar, a washer carried by the bolt, a nut upon the latter and affording means whereby the bar may be held in different ad-

- justed positions upon a forked telephone receiver, and means for raising and lowering the receiver holder.
2. In combination with a telephone, an amplifier for attachment to the receiver of a telephone, a swivelly mounted clamping member fixed to said amplifier, a bar secured to said clamping member and designed to be adjustably held to the forked end of a telephone receiver holder, and a lever for raising and lowering the receiver holder.
3. In combination with a telephone, an amplifier for attachment to the receiver of a telephone, a swivelly mounted clamping

member secured to the amplifier, a bar fastened to the clamping member, a receiver holder and support therefor, a clamping member engaging said support and provided with an arm, a lever pivotally mounted upon said arm and having a forked end for engagement with the receiver holder, the latter being connected to said bar.

In testimony whereof I hereunto affix my signature in presence of two witnesses.

ROSA D. HATCH.
